(57) **CLAIM**

The ornamental design for a paper roll holder, as shown and described.

DESCRIPTION

FIG. 1 is a front elevational view of a paper roll holder according to my new design;

FIG. 2 is a top plan view thereof;

FIG. 3 is a side elevational view thereof;

FIG. 4 is a rear elevational view thereof; and,

FIG. 5 is a bottom plan view thereof.

The broken-line disclosure is understood to represent portions of the article in which the claimed design is embodied, but which form no part of the claimed design.

1 Claim, 4 Drawing Sheets

FIG. 1

FIG. 2

FIG. 5

FIG. 3

FIG. 4
